UNITED STATES PATENT OFFICE.

WALTER J. PIKE AND WILLIAM J. GIBSON, OF NEWAYGO, MICHIGAN, ASSIGNEES TO THE PIKE LABORATORIES LIMITED, OF NEWAYGO, MICHIGAN, A LIMITED CO-PARTNERSHIP OF MICHIGAN.

VEHICLE HEADLIGHT.

Application filed October 6, 1923. Serial No. 666,892.

The present invention relates to head lights for automobiles and the like, and more particularly to a lamp construction adapted not only to prevent glare but also arranged 5 so as to throw all of the light beams on the roadway in front of the vehicle in such a manner as to properly and effectively illuminate the road. This present construction combines the use of the original parabolic 10 reflector with a covering lens or plate having a light emitting opening only at the center and a hood extending in front of this lens or plate so arranged as to prevent light rays from rising above the level of the axis 15 of the lamp and thus preventing glare to operators of on-coming vehicles. To the accomplishment of the foregoing and related ends, said invention, then, consists of the means hereinafter fully described and particularly pointed out in the claims. 20

The annexed drawing and the following description set forth in detail certain mechanism embodying the invention, such disclosed means constituting, however, but one 25 of various mechanical forms in which the principle of the invention may be used.

In said annexed drawing:—

Fig. 1 is a vertical sectional view through a lamp embodying the present invention; 30 Fig. 2 is a similar sectional view showing a modified form of construction, and Fig. 3 is a section taken on the line 3—3 of Fig. 2.

The present headlight comprises the usual outer casing 1 carrying the lamp socket 2, 35 lamp bulb 3 and electrical connections therefor. Within this casing is mounted the usual parabolic reflector 4. In place of the usual lens mounted at the front of the reflector, is a second parabolic reflector 5, 40 turned in the reverse direction to reflector 4, having a central aperture 6, this reflector being of a longer focal length than the main reflector. Mounted in the opening at the center of the reversely positioned reflector 45 5 is a headlight lens 7 of the type commonly used to bend the light rays downwardly, and over and around this lens is mounted a forwardly and downwardly extending hood 8 which is preferably polished 50 on its lower or inner surface 9 so as to reflect light rays which strike the same downwardly onto the road. As shown in Fig. 1, a washer 10 is mounted between the flanged ends of the two reflectors and these are held

in place by means of a locking ring 11 or 55 the like, which is mounted upon the edge of the outer casing.

In Fig. 2 there is shown a similar lamp construction embodying an outer casing or housing 12 carrying the lamp socket 13, 60 lamp 14 and electrical connections and the usual parabolic reflector 15 mounted in the casing. Over the front of this casing, in place of the usual lens, is mounted a plate 16 having an opening 17 in the center similar to the opening in the reversely positioned parabolic reflector such as shown in Fig. 1. The forwardly and downwardly extending hood 8 is attached to this plate surrounding the opening and within the opening is mounted the same type of non-glaring lens 7. The inner surface of this plate will preferably be a reflecting surface, although it may be unpolished for use under certain 65 conditions. 70

In using a headlight of this type it has been found that the light rays which would normally go out through the center of the lens are transmitted directly through the small lens placed at the center of the second reflector or plate and are used for the main forwardly extending beam of light in the usual manner. The headlight will be tilted slightly, as is the usual practice, and as it is the central portion of the rays which 80 gives the greatest illumination, this portion is maintained by the present light. The rays coming from the main reflector strike the reversely positioned reflector, are reflected back against the main reflector and 85 then out through the lens either downwardly against the ground in front of the vehicle or against the polished inner surface of the hood from which they will be reflected downwardly onto the road. The use 90 of a flat plate such as is shown in Fig. 2 serves substantially the same purpose in reflecting the rays within the headlight back against the main reflector and finally out through the small centrally placed lens. 100 The hood, as shown in both figures, extends downwardly, that is, at an angle to the axis of the lamp and thus prevents rays of light coming directly from the bulb through the lens and traveling in an upward direction, thus eliminating the glare 105 from the direct rays from the bulb and also preventing rays of light from being reflected

from the main reflector in an upward direction. The use of the usual type of non-glaring lens which tends to bend the light rays slightly downward also aids in overcoming the upward rays of light which give the glaring effect.

By the use of this downwardly directed hood and the small lens, both the lens and the light-giving bulb, as well as the reflector proper are entirely concealed from the view of the driver of an approaching vehicle, while at the same time giving the user the benefit of the entire light on the road. The use of this hood also takes care of the improper focusing of the lamp, and while such improper focusing of the lamp bulb will reduce the light given out by the headlight and will cut down the road illumination, it causes trouble only to the user of the vehicle on which the present lights are installed and does not cause any glare to drivers of vehicles which may approach one on which headlights are used. As is well known, the ordinary non-glaring headlight is not particularly effective and always glares to some extent. With the present headlight and hood arrangement the rays of light are directed onto the road so as to properly illuminate the same, but at the same time the light giving elements comprising the bulb, reflector and lens are substantially concealed from the drivers of approaching vehicles so that there is no danger of any glare to them.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a headlight for motor vehicles, the combination with a casing, lamp socket and lighting element of a parabolic reflector positioned in said casing, a second parabolic reflector mounted at the front of said casing, and positioned reversely with respect to said first reflector, said second reflector being of greater focal length than said first reflector and being provided with a central opening, a light directing lens mounted in such opening, and a forwardly extending elongated inclined hood surrounding said lens and rigidly secured to said second reflector, said hood being polished to provide a reflecting inner surface and being so placed as to cut off all upwardly directed light rays from said lens and to reflect the same onto the ground in front of the vehicle.

2. In a headlight for motor vehicles, the combination with a casing, lamp socket and lighting element, of a parabolic reflector positioned in said casing, a reflecting plate mounted across the open end of said reflector and provided with a central opening, a light directing lens mounted in such opening in said plate and an elongated hood rigidly attached to said plate about said lens, said hood being open at the bottom and having its upper surface inclined downwardly toward the axis of the reflector but terminating slightly above such axis, the sides of said hood inclining upwardly from points near the bottom of such opening to less than a half circle at the front end of said hood.

Signed by us, this 22nd day of September, 1923.

WALTER J. PIKE.
WILLIAM J. GIBSON.
